UNITED STATES PATENT OFFICE.

HENRY G. THOMPSON, OF CLEVELAND, OHIO.

PRESSED-METAL ARTICLE.

Application filed May 31, 1922. Serial No. 565,005.

To all whom it may concern:

Be it known that I, HENRY G. THOMPSON, a citizen of the United States, residing at Cleveland, in the county of Cuyahoga and State of Ohio, have invented a certain new and useful Improvement in Pressed-Metal Articles, of which the following is a full, clear, and exact description.

This invention relates to a pressed metal article which may be broadly described as comprising a central base portion by which it may be attached, and an arm or hook-like extension, or there may be two oppositely disposed arms or hook-like extensions.

One of the uses to which such an article may be put is that of forming a hook by which ropes may be fastened, which ropes are associated with pulleys.

It is to be understood, however, that the invention is not limited to a construction for this precise purpose.

The article is initiated by forming a blank out of sheet metal, and by the use of dies the metal is folded and formed until it produces the finished article.

Referring to the drawings, Fig. 1 is a plan view of a blank; Fig. 2 is a top plan view of the device when it has been partially folded and formed; Fig. 3 is a side elevation of the showing in Fig. 2; Fig. 4 is a side elevation of the completed article; Fig. 5 is a bottom plan view of the completed article; Fig. 6 is a top plan view of the completed article; Fig. 7 is a section on the line 7-7 of Fig. 6, and Fig. 8 is a section on the line 8-8 of Fig. 6.

Referring to the drawings, and more particularly Fig. 1, there is shown a blank which has a central portion 1 with extending arms 2 and 3. These arms at their outer ends are slightly tapered, as indicated at 2^a and 3^a.

At the inner end of each arm there are outwardly extending pointed portions 2^b and 3^b, and adjacent these pointed portions are notches 2^c and 3^c. This blank is also provided with one or more suitable openings, such as indicated at 4, these openings being formed at the same time that the blank is cut out of the sheet metal.

In the first operation the metal is bent to provide upwardly extending side flanges 1^a and 1^b which are formed at the side or edge of the central portion 1, and the outer edges of the arms are also formed up into up-

standing flanges, which are indicated at 2^d and 3^d.

In this operation the central openings 4 may be countersunk, thereby providing an upraised rib or bead surrounding them, such as indicated at 4^e.

Preferably at the same time that the flanges 2^d and 3^d are being formed, although not necessarily, the arms 2 and 3 are formed up to extend away from the central portion 1, and to assume a curved position, such as indicated in Fig. 3. This operation of flanging the blank and curving the arms may be performed simultaneously, although this is not necessarily the case.

On the next operation the edges of the flanges 2^d and 3^d are rolled toward each other until the edges meet, thus forming hollow arms, so that the section through any portion of one of the arms is approximately a circle. The diameter of any such cross section, however, will vary slightly from the outer end of the arm toward the inner end. At the same time the flanges 1^a and 1^b are rolled inwardly until the edge of the flange contacts with the central portion 1, and in doing this it may be desirable or necessary to slightly cut out a portion of the flanges 1^b and 1^a, as indicated at 1^f, for the purpose of accommodating the beads which are formed around the openings 4. The pointed portions 2^b and 3^b will fold against the central portion 1 at the end thereof, and provide the slight amount of extra metal needed in order to provide for the widened portion of the arm adjacent the part where it adjoins the central portion.

It will thus be seen that the article as described is formed from a single blank, and when the article is finished it has all the appearance of being solid, and has even greater strength than the solid article would have, particularly against distortion or breakage, particularly of a similar article which was made of cast metal.

Having described my invention, I claim:

1. The method of forming a hook-like article which comprises blanking out of sheet metal a blank having a central portion and oppositely extending arms, forming said blank by moving the edges of the said arm portion and the central portion to provide upstanding flanges, then rolling over the edges of the flanges on the arms

into substantial contact thereby forming hollow tubular arms, and rolling the flanges formed in the central portion into contact with the central portion thereby forming a bead at the edges of the central portion which are contiguous with the arms.

2. The method of forming a hook-like article which comprises blanking out of sheet metal a blank having a central portion and oppositely extending arms forming said blank by moving the edges of the arm portion and the central portion to provide flanges which flanges are on the same side of the blank, also forming the said arm portions in a gradual curve with respect to the central portion and out of the plane of the central portion, subsequently rolling over the edges of the arm members into substantial contact with each other thereby to form tubular arms, and rolling over the edges of the flanges on the central portion into contact with the central portion thereby forming beads at the edges of the central portion which are contiguous with the arms.

25 3. The method of forming a hook-like article which comprises blanking out of sheet metal a blank having a central portion, an

extending arm forming said blank by moving the edges of the arm and central portion to form flanges, then rolling over the edges of the arm into substantial contact thereby forming a hollow arm and rolling over the edges of the flanges on the central portion to form upstanding beads at the edges of the central portion.

4. The method of forming a hook-like article which comprises blanking out of sheet metal a blank having a central portion and an extending arm, forming said blank by moving the edges of the arm and central portion to form upstanding flanges, and also forming the arm in a gradual curve with respect to the central portion and out of the plane of said central portion, and subsequently rolling over the edges of the flanges on the arm into substantial contact thereby forming a hollow arm, and rolling over the flanges on the central portion into contact with the central portion thereby forming beads at the edge of the central portion.

In testimony whereof, I hereunto affix my signature.

HENRY G. THOMPSON.
